(57) **CLAIM**

The ornamental design for a syringe drive device, as shown and described.

DESCRIPTION

FIG. 1 is a top perspective view of a syringe drive device of the present invention;

FIG. 2 is a front view thereof;

FIG. 3 is a rear view thereof;

FIG. 4 is a first side view thereof;

FIG. 5 is a second side view thereof;

FIG. 6 is a top view thereof;

FIG. 7 is a bottom view thereof; and,

FIG. 8 is a top perspective view thereof shown in an alternate environment, with the device in an extended configuration.

The dash dot lines immediately adjacent to the shaded areas in the views represent the boundaries of the claimed design. The dashed lines in the figures illustrate the portions of the design that form no part of the claimed design. None of the broken lines form any part of the claimed design.
